UNITED STATES PATENT OFFICE.

JACOB J. VIENNEAU, OF PITTSFIELD, MASSACHUSETTS, ASSIGNOR TO GENERAL ELECTRIC COMPANY, A CORPORATION OF NEW YORK.

COIL-WINDING MACHINE.

Application filed June 1, 1922. Serial No. 565,203.

To all whom it may concern:

Be it known that I, JACOB J. VIENNEAU, a citizen of the United States, residing at Pittsfield, in the county of Berkshire, State 5 of Massachusetts, have invented certain new and useful Improvements in Coil-Winding Machines, of which the following is a specification.

My invention relates to coil winding machines and has for its object the provision of means whereby the coil may be more compactly and uniformly wound.

More specifically my invention relates to automatic machines for winding electrical 10 conductors and the like into coils. My invention is particularly applicable to the winding of transformer coils, field coils, etc. In order to make a more compact and uniform winding, it is common to wind each 15 turn along a circumference of the spool rather than to make the winding in the form of a helix. When winding coils in this manner, the conductor is shifted at the end of each turn into the next succeeding 20 turn and at the end of each layer the shifting movement is reversed for the next layer. With present types of automatic winding machines which introduce the shifting movements in unbroken succession, the 25 first turn of each layer falls at one side instead of directly upon the last turn of the preceding layer. A gap is thus left between the first turn of each layer and the end of the spool equal in width to the amount of the 30 shifting movement which ordinarily is equal to the width of the conductor. It follows that this method of winding results in loss of available space on the spool as well as in a non-uniform winding.

In carrying out my invention, I have provided means for delaying or interrupting the shifting movement at the end of each layer, whereby the first turn of each layer 35 may be wound in a predetermined relation 40 with the last turn of the preceding layer so as to form a more compact and uniform winding. In one embodiment of my invention, I provide a lost motion driving connection between the shifting means and the 45 feeding device. The arrangement is such that when the shifting means is reversed at the end of each layer, the first shifting movement of each layer, or, in other words, the 50 shifting movement in the reversed direction immediately after the end of the preceding

layer, may be restricted or cancelled altogether, as desired, whereby the first turn may be made to fall directly upon or in any predetermined relation with the last turn of the preceding layer.

For a better understanding of my invention, reference should be had to the accompanying drawings, in which Fig. 1 is a partial view in perspective of a winding machine embodying my invention; Fig. 2 is a 60 sectional view showing the adjustable lost motion connection; Fig. 3 is an elevation view of Fig. 2; Fig. 4 is a view in perspective of the two cooperating parts of the lost motion coupling shown in Figs. 2 and 3; 65 Figs. 5 and 6 are partial section views showing a typical arrangement of the turns with round and square conductors, respectively, when using my invention; while Fig. 7 shows a modified form of my invention. 70

Referring to Fig. 1 of the drawing, although I have shown my invention embodied in a specific type of automatic coil winding machine the details of which form no part of my invention, it will be obvious that it 75 may be applied to various other types of coil winding machines. In the specific mechanism shown, the spool 10 is carried on a shaft 11 which is driven by means of a chain 12 cooperating with a sprocket wheel 13 secured to the shaft. The spool may be releasably secured to the shaft 11 so that it 80 may be removed upon the completion of the winding operation, or the spool may be arranged in parts to permit the removal of the 85 coil after being wound. As shown in the drawing, the electric conductor 14 or other material to be wound is guided over two rollers 15 and 16 so as to be wound in layers 90 on spool 10 as it is rotated. The guiding 95 rollers 15 and 16 are carried on a suitable frame 17 which is constrained to move on guide-bars 18 and 19 in a direction parallel with the axis of shaft 11.

The frame 17 is moved by an amount 100 equal to the diameter of the conductor upon the completion of each turn, whereby the conductor 14 is shifted into the next turn, each turn lying in a plane perpendicular to the axis of the coil, or, in other words, along 105 a circumference of the coil. A winding is thus formed of the type shown in Fig. 5. This periodic shifting movement is transmitted to the frame through a screw shaft 110 20 cooperating with a suitable nut 21 opera-

tively connected to the frame. A ratchet driving wheel 22 is secured to the left-hand end of shaft 20, and cooperating with the ratchet wheel are driving pawls 23 and 24, 5 one or the other of which is adapted to engage the ratchet wheel depending on the direction in which the frame 17 is being moved. The pawls 23 and 24 are pivotally mounted on arms 25 and 26, which are in 10 turn pivotally mounted on shaft 20, and are biased to positions to engage ratchet wheel 22 by means of spiral springs 27 and 28. Arms 25 and 26 are operatively connected to a slider 30 moving on a guide 31 by 15 means of links 32 and 33. Carried by slider 30 is an adjustable pin 34 which extends through an arc-shaped slot 35 in a lever 36 pivoted on a fixed post 37. The pin 34 is shown secured on the end of an arm 34' 20 which is adjustable about its point of support on slider 30, whereby pin 34 may be adjusted in slot 35. On the upper end of lever 36 is a roller or pin 38 which moves in a cam slot 39 in a disk 40 secured to the 25 end of shaft 11. The cam slot 39 is formed in such manner that as shaft 11 is rotated, lever 36 will be rocked about its pivot, its movement being transmitted to slider 30 and through links 32 and 33 to arms 25 and 30 26 so that the ratchet driving wheel 22 will be rotated periodically through a small arc once each revolution of shaft 11 in a direction depending on which pawl 23 or 24 is 35 in engagement with it. Frame 17 is thus moved once each turn of spool 10 to shift the conductor into the next succeeding turn. The amount of this shifting movement can be regulated to correspond with the size of the conductor by varying the movement 40 given slider 30 by means of the adjustment provided for pin 34 in slot 35.

For the purpose of controlling the engagement of pawls 23 and 24 with the ratchet wheel, the pawls are provided with 45 actuating arms 40 and 41 having cam faces which are adapted to engage with opposite sides of a disk 42 carried by a sleeve 43 loosely mounted on shaft 20. When disk 42 is in the position shown in the drawing, 50 it engages arm 41, holding pawl 24 out of engagement with ratchet wheel 22, while arm 40 is free whereby pawl 23 is held in engagement with the ratchet wheel by spring 27. When disk 42 is moved to the left, it 55 will engage arm 40, lifting pawl 23, and free arm 41, whereby pawl 24 is moved into engagement with the ratchet wheel by spring 28. The position of disk 42 is controlled by means of a yoke 44 cooperating with sleeve 60 43 and provided with an extension parallel with shaft 20 in which are nicks 45 and 46. Pawls 47 and 48 are provided adjacent opposite sides of this extension and are biased 65 toward it so as to cooperate with nicks 45 and 46, respectively, by a spiral spring 49.

These pawls are carried on an arm 50 secured at its center at right angles to a shaft 51 which also carries an arm 52 cooperating with a lever 53. On the opposite end of lever 53 is a pin 54 which moves in a cam 70 groove 55 in a collar 56 rigidly secured to shaft 11. The cam groove 55 is generated so that arm 53 is rocked in a clockwise direction once each revolution of shaft 11, which movement is transmitted through 75 shaft 51 to the pawls 47 and 48.

Adjacent pawls 47 and 48 are upright bars 60 and 61 which are biased in upward and downward directions respectively by spiral springs 62 and 63. On the bars 60 80 and 61 are pins 64 and 65 lying in the path of pawls 47 and 48 so as to normally hold the pawls out of nicks 45 and 46. The bars 60 and 61 are operatively connected through pin and slot connections to a transverse rod 66 extending parallel with shaft 20 and through frame 17. On the rod 66 are adjustable collars or stops 67 and 68 lying on opposite sides of frame 17, one of which is in position to be engaged by the frame as 85 it nears the completion of its movement in either direction. The rod 66 is normally biased to a central position by means of a lever 69 provided with a centering spring 90 70. Rigidly secured to shaft 20 are adjustable arms 71 and 72 which are adapted to cooperate respectively with projections 73 and 74, carried by bars 60 and 61, when rod 66 is moved by frame 17. The distance between projections 73 and 74 is considerably 100 less than the distance between arms 71 and 72. The projections are normally biased by centering spring 70 in a central position between the arms so as not to be engaged thereby as shaft 20 rotates.

The operation of this reversing mechanism is as follows: Upon the completion of a layer of the winding on spool 10, frame 17 will engage one or the other of stops 67 and 68 giving rod 66 movement of translation so 110 as to bring one or the other of projections 73 and 74 in position to be engaged by the corresponding arms 71 or 72. Assuming, for example, that rod 66 is moved toward the left, upon the next rotative shifting movement transmitted to shaft 20, arm 71 will engage projection 73 depressing upright bar 60. This releases pawl 47, which will be moved by spring 49 into nick 45, and upon the rocking of lever 53 in a clockwise direction during the next turn will be actuated to move yoke 44 and hence disk 42 toward the left. Pawl 24 is thus released and pawl 23 lifted so that the next shifting movement 115 at the end of the turn will be given to frame 17 by pawl 24 and will be in the opposite direction, being the beginning of the next layer of the winding. Frame 17 will then disengage stop 68, which is thereupon moved 120 by centering spring 70 toward the left to its 125 130

central position in which projections 73 and 74 are between arms 71 and 72.

The driving nut 21 is provided with an oblique groove 75, cooperating with which 5 is a pin carried by the end of an upright bar 76 moving in a guide 77 in frame 17 and cooperating at its lower end with a guiding bar 78. The bar 76 thus forms the operating connection between nut 21 and frame 17.

- 10 By adjusting bar 78 at an angle with guide bar 19, the arm 76 may be given movement of translation in its guide 77 as frame 17 is moved. In such case it will be observed that frame 17 will be given a slight movement 15 independently of nut 21 due to the effect of the oblique slot 75, and the direction and amount of this movement will depend on the direction and amount of the angle at which guide 78 is set with relation 20 to guide 19. This independent movement of frame 17 is provided for more accurate adjustment for the width of the conductor than can be made by adjusting pin 34 in slot 35.

- 25 The apparatus thus far described for automatically winding coils, which forms no part of my present invention, has the disadvantage that upon the completion of each layer of the winding, frame 17 will be immediately shifted in the opposite direction 30 so that the first turn of the next layer will be displaced along the axis of the coil with relation to the last turn of the preceding layer, so as to fall upon the next to the 35 last turn of the preceding layer. A gap is thus left between the first turn of each layer and the end of the spool equal in width to the amount of the shifting movement which is ordinarily equal to the width of the conductor. It will be noted that with this 40 method of winding there is a loss of space on the coil and furthermore the last turn of any layer has a tendency to drop into the gap left by the first turn of the preceding layer, thus forming an irregular winding. 45 Also, where a round conductor is used, the first turn of each layer has a tendency to drop into the gutter between the turns of the preceding layer, thus further disarranging 50 the winding.

Referring to Figs. 1 to 4, inclusive, of the drawing, in carrying out my invention in one form I interpose a lost motion coupling 80 in shaft 20. This coupling comprises two 55 cooperating flanges 81 and 82. The shaft 20 is formed in two sections 20^a and 20^b, one of which carries a trunnion which fits in a corresponding recess in the other section, thus maintaining the sections in alignment. Section 60 20^a is shown as provided with a transverse rectangular projection 83 which moves in central, arc-shaped slots 84 and 85 in flanges 81 and 82 respectively. Flange 82 is rigidly secured to section 20^b, for example, 65 by means of a pin 86, while flange 81 is

loosely mounted on section 20^a. The two flanges 81 and 82 are held together by diametrically opposite bolts 87 and 88 secured to flange 82 and extending through arc-shaped slots 89 and 90 in flange 81 whereby 70 the relative angular positions of the flanges can be adjusted so as to regulate the freedom of projection 83 in slots 84 and 85, and hence the freedom of section 20^a with relation to section 20^b. It will be observed that when 75 the slots 84 and 85 are aligned, projection 83 has its greatest freedom of movement. This movement can be regulated from this maximum to zero by displacing the flanges.

With this coupling interposed in shaft 20, 80 it will be observed that when the movement of frame 17 is reversed at the end of each layer, the first shifting movement in the reversed direction may be partially or wholly taken up by the lost motion in the coupling. 85 The frame may be moved, for example, only half the width of the conductor for the gutter winding, as shown in Fig. 5, or with a square conductor the first shifting movement in each layer may be entirely taken 90 up by the lost motion coupling, whereby the first turn of each layer will be placed directly upon the last turn of the preceding layer, as shown in Fig. 6. Very compact and uniform windings may thus be formed. 95 The amount of this lost motion may be adjusted to correspond with the size of the conductor being wound by turning flange 81 with relation to flange 82. Flange 81 may be provided with a scale 91, and flange 100 82 with a cooperating mark 91', whereby this adjustment may be accurately made.

In the modification of my invention shown in Fig. 7, I have provided means for adjusting the width of the oblique slot 75 105 in nut 21, thus providing a lost motion connection at this point. When using this arrangement, the coupling 80 will not be used. The width of slot 75 may be conveniently adjusted by providing a slider 92 which 110 may be adjusted by screws 93 with relation to a shoulder 94 forming the opposite side of the slot.

While I have described my invention as embodied in concrete form and as operating 115 in a specific manner in accordance with the provisions of the patent statutes, it should be understood that I do not limit my invention thereto, since various modifications thereof will suggest themselves to those 120 skilled in the art without departing from the spirit of my invention, the scope of which is set forth in the annexed claims.

What I claim as new and desire to secure by Letters Patent of the United States, 125 is:

1. A coil winding machine for electrical conductors and the like comprising in combination with a spool, means for turning said spool and for feeding said conductor 130

along a predetermined circumference of said spool, means for shifting said feeding means from one turn to the next, means for reversing said shifting means at the end of each layer, and means for delaying the action of said shifting means in the reverse direction so as to wind the first and last turns of successive layers in a different axial relation than adjacent turns of the 10 same layer.

2. A coil winding machine for electrical conductors and the like comprising in combination with a spool, means for turning said spool and for feeding said conductor 15 along a predetermined circumference of said spool, means for shifting said feeding means from one turn to the next, means for reversing said shifting means at the end of each layer, and means for delaying the 20 action of said shifting means at the end of each layer whereby the first and last turns of successive layers may be wound in a predetermined relation.

3. A coil winding machine for electrical 25 conductors and the like comprising in combination with a spool, means for turning said spool and for feeding said conductor along a predetermined circumference of said spool, means for shifting said feeding 30 means from one turn to the next, means for reversing said shifting means at the end of each layer, and means for delaying the 35 action of said shifting means simultaneously with its reversal so as to cause the first turn of each layer to take a predetermined posi-

tion with relation to the last turn of the preceding layer.

4. A coil winding machine for electrical conductors and the like comprising in combination with a spool, means for turning 40 said spool and for feeding said conductor along a predetermined circumference of said spool, means for shifting said feeding means from one turn to the next, means for reversing said shifting means at the end of 45 each layer, and a lost motion driving connection for said shifting means whereby its action is delayed so as to cause the first turn of each layer to fall in a predetermined position with relation to the last turn of 50 the preceding layer.

5. A coil winding machine for electrical conductors and the like comprising in combination with a spool, means for turning 55 said spool and for feeding said conductor along a predetermined circumference of said spool, means for shifting said feeding means from one turn to the next, means for reversing said shifting means at the end of each layer, and a lost motion driving connection 60 between said shifting means and said feeding means whereby the shifting movement is temporarily interrupted simultaneously with its reversal so as to cause the first turn of each layer to fall on the 65 last turn of the preceding layer.

In witness whereof, I have hereunto set my hand this 29th day of May, 1922.

JACOB J. VIENNEAU.
